UNITED STATES PATENT OFFICE.

HENRY S. DODD, OF TORONTO, ONTARIO, CANADA, ASSIGNOR TO JAMES R. L. STARR,
OF TORONTO, ONTARIO, CANADA.

ELECTRIC IRON.

Application filed June 13, 1921. Serial No. 477,155.

To all whom it may concern:

Be it known that I, HENRY S. DODD, a subject of the King of Great Britain, and resident of the city of Toronto, county 5 of York, Province of Ontario, in the Dominion of Canada, have invented certain new and useful Improvements in Electric Irons, described in the following specification and illustrated in the accompanying 10 drawings, that form part of the same.

The principal objects of this invention are, to obviate the dangers incident to the use of electric irons through the users inadvertently leaving them connected with the 15 current, and to provide a switch mechanism for cutting off the current, which will be operated in the normal act of handling the iron.

A further object is to devise a switch 20 control which may be readily attached to an iron and which will be of a strong and durable nature.

The principal features of the invention consist in the novel construction and arrangement of parts, whereby a pivotal switch member is operated by a longitudinally movable member controlled by a pivotal member arranged in the handle of the iron, and whereby said switch is mounted 30 in a detachable insulating unit.

In the drawings, Figure 1 is a perspective view of an iron constructed in accordance with this invention, a portion of the switch casing being broken away.

Figure 2 is a longitudinal mid-sectional view showing the iron set upon its end to maintain the electrical connection closed, for the preheating of the iron.

Figure 3 is a transverse sectional view 40 through the insulator block showing the connection with one of the heating element terminals.

Figure 4 is a view similar to Figure 3 showing the connection to one of the switch 45 terminals.

It is well known to those conversant with the art that the use of switches in electric irons has been unsuccessful and that practically all irons being marketed at the present time have a block or plug connector which is placed upon the terminals when the heat is required and pulled off when there is enough heat. This condition is highly unsatisfactory and has been the cause of 50 considerable fire loss through irons being

forgotten, and it is the purpose of this invention to produce an electric switch which will be very positive in its action, will minimize the element of sparking and will not retain a closed circuit unless the operator deliberately intends to leave it so connected.

In carrying this invention into effect I have equipped an iron so that the heater element terminals 1 and 2 extend into an insulator block 3 which is fastened to the iron 60 casing 4.

The terminal 2 is connected by a screw 5 to a plate 6 which extends laterally in the block and projects above the surface thereof to be connected to the ordinary plug. 70

A plate 7 having an end corresponding with that of the plate 6 is embedded in the block 3 to form the other connector with the plug and to this plate is secured a screw terminal 8 which extends downwardly through 75 the block and is threaded in said plate.

The block is formed with a parallel pair of ribs 9 with the top surface arranged longitudinally of the iron which ribs are adapted to fit inside the switch casing 10 to positively locate it. The iron handle 11 is supported by the U-shaped metal member 12 and to the back member of this metal support is secured an insulating block 13. 80

In the block 13 is embedded a pair of 85 metal contacts 14 and 15. The contact 14 is secured to the terminal 1 by a screw 16 and the contact 15 with the terminal screw 8 by a flexible connection 17.

The upper ends of the contacts 14 and 15 90 are exposed and are adapted to be bridged by a switch member to close the electric circuit to the heating element.

A sheet metal member 18 is formed in a substantially channel shaped structure, the 95 lower end thereof being secured to the insulating block 13 by the screws 19. The side walls of the member 18 at the top form a pair of lugs 20 and between these lugs is pivotally mounted the hollow metal member 21, which has an arm 22 extending upwardly from the centre and a stop lug 23 projects from the back. 100

A small pin 24 is secured on the inner side of each of the sides of the hollow metal member 21 below the pivot pin 25. These pins are adapted to extend into the notches 26 in the upper ends of the parallel arms 27 of a switch member 28 which at its lower end is provided with an insulator block 29 110

and in which is secured a roller pin 30 supporting on the outer ends the roller contacts 31, which are adapted to engage the contacts 14 and 15 to close the electrical circuit to the heating element.

The switch member is held in place by a coil spring 32 secured at the upper end to the pivotal pin 25 and extending downwardly and connected to a cross pin 33 extending 10 between the arms 27 of the switch member.

When the arm 22 of the hollow member 21 is in the forward position the small pins 24 will be in rearward relation with a straight line between the pivot pin 25 and the cross pin 33 and the tension of the spring will hold the contacts 31 in engagement with the fixed contacts.

Upon the swinging of the member 21 on its pivot the pins 24 will move forwardly 20 in the notches 26 and change the relative arrangement of the spring and the throwing over of the pivotal member 21 causes the said pins 24 to strike the forward side of the notches, thus throwing the switch in a backward direction which is accelerated by the spring 32. A very quick break of the electrical contact is thus made.

The casing 10 is secured by a screw 34 fastened in the member 21 and enclose the switch 30 and the contacts. The member 21 is operated by a tubular member 35 extending transversely through the top of the casing 10 to which it is pivotally connected. This tube extends into a tube 36 in the handle 11. 35 and it projects outwardly through the rear of the casing 10 and is adapted to be pushed in against the spiral compression spring 37 to throw the switch into electrical contact. Upon being released the tube 35 is forced 40 rearwardly by the spring 37 and automatically breaks the contact. The movement of the tube 35 is limited by a cross pin 38 which extends through slots 39 in said tube.

A slot 40 is cut in the bottom side of the tube 35 and a corresponding slot is cut in the tube 36.

A link 41 is pivotally secured toward the forward end of the tube 35 and the rearward end is adapted to swing outwardly through 50 the slots in said tubes. To the outer end of this link is connected a pivotal arm 42 secured at the forward end on a pivot pin 43 arranged in a slot in the underside of the handle. This arm is engaged by the fingers 55 of the person using the iron in the operation of ironing and is held in the position shown in Figure 2 with a very slight effort but upon being released the spring 37 forces the tube 35 backwardly to throw the switch out of 60 contact.

The casing 10 is provided with an indent 44 in the top in which is pivotally mounted a dog 45. This dog normally rests by gravity in the position shown in Figure 1 and the iron may be placed on its base end resting

upon the support 46 and upon this dog in the normal way. If it is desired to allow the current to remain on while the iron is resting on its base end a slight movement of the iron will cause the dog 45 to swing on its pivot 70 and allow the handle portion to drop. A slight downward pressure or a squeezing of the handle will throw the switch into the closed position and the weight of the iron will hold the switch closed as shown in Figure 2. It will remain in this position until lifted and the current will continue to flow as long as the squeezing pressure of the hand is maintained on the member 42 but immediately such pressure is released the compression spring 32 operates the switch in the manner described and breaks the contact. A very positive connecting switch with a quick cut out is thus produced and it will be seen that it operates automatically to cut out 80 whenever the iron is allowed to rest unless it is deliberately held in circuit by the action of the operator.

The construction is such as to render it readily adaptable for various forms of irons 90 as the switch terminals are flexibly connected with the terminals of the heater element.

The use of such an iron will effect the saving of a considerable amount of current and it will also prevent the destruction of materials and danger from fire as described.

Another feature of importance of the construction shown is that the metal handle is supported on insulating thimbles which prevent the heat from being conducted to the 100 switch mechanism from the body of the iron.

What I claim as my invention is:—

1. In an electric iron, the combination with a pair of terminals rigidly connected with the heater element, of a pivotal switch member adapted to close the circuit between said terminals, a reciprocable member supported in the handle and operatively connected with said switch, and means for operating said longitudinally movable member.

2. In an electric iron, the combination with a pair of terminals rigidly connected with the heater element, of a pivotal switch member adapted to close the circuit between said terminals, a reciprocable member supported in the handle and operatively connected with said switch, and a member pivotally secured in the handle and operatively connected with said reciprocable member.

3. In an electric iron, the combination with a pair of terminals connected with the heater element, of a pivotal switch member adapted to close the circuit between said terminals, a reciprocable member supported in the handle and movable longitudinally thereof to operate said switch, a link pivotally connected to said longitudinally movable member and adapted to swing outwardly therefrom, and an arm pivotally con-

nected at one end to said link and at the other end to the handle.

4. In an electric iron, the combination with a pair of terminals connected with the heater element, of a pivotal switch member adapted to close the circuit between said terminals, a member supported in the handle and movable longitudinally thereof to operate said switch, a compression spring arranged at the end of said member adapted to move it longitudinally, means for limiting its movement, an arm pivotally mounted at one end of the handle, and a link connected at the other end of said arm and to said longitudinally movable member to move it against said spring.

5. In an electric iron, the combination with a pair of terminals connected with the heater element, a rigid support adjacent to said terminals, a member pivotally mounted on said rigid support, a switch member adapted to engage said terminals and supported from said pivotal member, a coil tension spring connecting said switch member with the pivot pin of said pivotal member, means carried on the pivotal member for throwing the switch member into and out of contact with said terminals, and means arranged in the handle for swinging said pivotal member.

6. In an electric iron, the combination with a pair of terminals connected with the heater element, a rigid support adjacent to said terminals and having a parallel pair of lugs at the top, a member pivotally supported between said lugs and having an open centre, short pins extending inwardly from the sides of said pivotal member, a switch member having side arms formed with notches at the top engaging said pins, a

cross bar between said side arms, a spiral tension spring secured at one end to said cross bar and at the other end to the pivot pin of the pivotal member, and means arranged in the handle for swinging said pivotal member.

7. In an electric iron, the combination with the heater element and terminals thereof, of an insulator block having plug connections embedded therein adapted to be connected with the terminals, an insulator block fitting on the aforesaid block and having a pair of terminals electrically connected with the terminals in the aforesaid block, a metal member secured to the latter insulating block, a switch arm pivotally supported on said metal member adapted to join the terminals carried by said block, means carried by said member for operating said switch with a snap action, and means arranged in the handle adapted to operate the switch operating member.

8. In an electric iron, the combination with the handle, of an insulating block secured to the iron casing and having a pair of terminal posts embedded therein, a secondary insulating block rigidly connected to the handle and abutting the aforesaid block and having a pair of terminals embedded therein, a switch member adapted to close an electrical circuit to the latter terminals, a casing enclosing said switch mechanism, a reciprocating member operating in the handle adapted to operate said switch mechanism and projecting through said casing, and a pivotal member secured to said casing and adapted to support the iron when placed upon its base end to prevent the movement of the switch operating member.

HENRY S. DODD.
